UNITED STATES PATENT OFFICE.

LYMAN MIDDLEITCH, OF NEW YORK, N. Y.

FEED MECHANISM FOR PRINTING-PRESSES AND OTHER MACHINES.

1,151,808.

Specification of Letters Patent. Patented Aug. 31, 1915.

Application filed June 28, 1910. Serial No. 569,300.

To all whom it may concern:

Be it known that I, LYMAN MIDDLEITCH, a citizen of the United States, and a resident of the city of New York, borough of Manhattan, in the county and State of New York, have invented a new and Improved Feed Mechanism for Printing-PresSES and other Machines, of which the following is a full, clear, and exact description.

10. The invention relates to high speed printing presses of the bed and cylinder or other type, and its object is to provide a new and improved feed mechanism arranged for feeding the sheets of paper singly and in 15 rapid succession to the printing press or other machine without the aid of skilled labor.

For the purpose mentioned, use is made of means for moving the uppermost sheet 20 of a pile of sheets gradually rearward, and means for engaging the uppermost sheet and drawing it forward off the pile of sheets.

A practical embodiment of the invention is represented in the accompanying drawings forming a part of this specification, in 25 which similar characters of reference indicate corresponding parts in all the views.

Figure 1 is a plan view of the feed mechanism as applied to a rotary press; Fig. 2 is 30 a sectional side elevation of the same on the line 2—2 of Figure 1; Fig. 3 is a similar view of the same and showing the parts in a different position; Fig. 4 is an enlarged sectional side elevation of the rearward 35 combing means, the section being on the line 4—4 of Fig. 1; Fig. 5 is a similar view of the same showing the parts in a different position; Fig. 6 is a cross section of the feed mechanism on the line 6—6 of Fig. 2; Fig. 40 7 is an enlarged cross section of part of the rearward combing mechanism, the section being on the line 7—7 of Fig. 1; Fig. 8 is an enlarged side elevation of the mechanism for actuating the forward conveying 45 means; and Fig. 9 is a cross section of the bearing for the combing wheel shaft.

The forwardly and downwardly-inclined feed table A of the printing press supports a pile of sheets B, and is mounted on the rear 50 end of the main frame C of the printing press, having feed rollers D, D' for passing

the sheets B successively over the rollers D' to the grippers of the printing press cylinder, in the usual manner.

The sheets B are moved intermittently 55 forward, either by hand, but, preferably by the use of one or more endless belts E, passing over wheels E', E'', mounted to rotate on the under side of the feed table A in such a manner that the upper run of each belt E 60 passes over the top of the feed table A and hence underneath the lowermost sheet of the bank or pile of sheets B. An intermittent rotary motion is given to the forward wheel E' from a transverse shaft F journaled on the main frame C and driven from one of the rotary parts of the printing press. On the shaft E' of the wheel E' is secured a ratchet wheel G, engaged by a spring-pressed pawl G', fulcrumed on the arm G'', 70 mounted to swing loosely on the shaft E', and pivotally connected with a rod G' extending from a cross head G'', mounted to slide on the shaft F above mentioned. On the cross head G'' is mounted a roller G'', adapted 75 to be engaged by cam G' secured on the shaft F, so that when the latter is rotated the cam G' engages the roller G'', to impart a rearward sliding motion to the cross head G'', thus causing swinging of the arm G'' 80 which, by the pawl G' and the ratchet wheel G, rotates the wheel E', to impart a traveling motion to the belt E in the direction of the arrows a' indicated in Figs. 2 and 3. The return movement of the cross head G'', 85 arm G'' and pawl G' is accomplished by a spring G' connected with the cross head G'', as indicated in Figs. 2, 3 and 8. By imparting an intermittent traveling motion to the belt E, the pile of sheets B is moved intermittently forward, and the forward ends thereof are moved in contact with arch-shaped springs or plates H, secured at their forward ends to a bracket H', projecting from the forward end of the feed table A. 90 By the arrangement described, the pile of sheets B is gradually conveyed in a forward direction, and the uppermost sheets finally pass over the crown of the springs or plates H into a guideway or space between the forward ends of the said springs or plates H and arms H'' secured to the forward ends 95

H and arms H'' secured to the forward ends

of the bracket H' (see Figs. 2 and 3). In case the sheets are fed too far forward into the space between the springs H and the arms H², to be taken care of by a feed mechanism, as hereinafter more fully described, then the most forward of the said sheets engages with its forward end an arm H³ of a bell crank lever, fulcrumed on the bracket H', and having its other arm H⁴ provided with a hook adapted to engage a tooth G⁸ arranged on top of the cross head G⁴. Thus when a sheet acts on the arm H³ and swings the same forward, then the hook of the arm H⁴ finally engages the tooth G⁸ at the time the cross head G⁴ is in its rearmost position, thus locking the cross head G⁴ against return or forward movement by the action of the spring G⁷, and hence the forward feeding of the pile of sheets B ceases as the traveling motion of the belt E is stopped for the time being. A spring H⁵ presses the arm H⁴ of the bell crank lever to return the same to normal position as soon as the sheet, which previously actuated the arm H³, has been combed rearwardly, so that the hook of the arm H⁴ releases the tooth G⁸ and the cross head is again actuated for imparting an intermittent traveling motion to the belt E. A stop H⁶ on the bracket H' limits the return movement of the arm H³ of the bell crank lever.

In order to comb the uppermost sheets of the pile of sheets B rearwardly, use is made of one, two or more combing wheels I, secured on a transverse shaft I', journaled in bearings J held adjustable on longitudinally-extending rods K, forming part of a swinging frame, and fulcrumed on a shaft L, carrying drawing rollers L' operating in conjunction with the free ends N' of swing arms N, for drawing the uppermost sheet B' off the pile of sheets B, and deliver it to and between the feed rollers D, D', as hereinafter more fully explained.

The combing wheels I are continually rotated in the direction of the arrows b', and for this purpose the shaft I' of the combing wheels I is driven from the shaft D³ of the uppermost feed roll D, and which shaft D³ is driven from a rotating part of the printing press. On the shaft D³ is secured a gear wheel O in mesh with a gear wheel O', secured on a transverse shaft O² journaled in a bracket C' attached to a cross rod C² of the main frame C, and on the said shaft O² is secured a bevel gear wheel O³ in mesh with a bevel gear wheel O⁴, mounted to turn with and to slide on a shaft O⁵, carrying at its rear end a bevel gear wheel O⁶, in mesh with a bevel gear wheel O⁷, secured on the shaft I' carrying the combing wheels I. The forward end of the shaft O⁵ is mounted to slide in a bearing C³, held to rock on the bracket C' in axial alignment with the shaft O², and the rear end of the shaft O⁵ is jour-

naled in a bearing I² held loosely on the shaft I' (see Fig. 1). A spring O⁸ is coiled on the shaft O⁵ and rests with one end against a collar O⁹, secured to the shaft O⁵, the other end of the spring O⁸ abutting 70 against the hub of the gear wheel O⁴, to hold the latter in mesh with its mate O³. From the foregoing it will be seen that when the printing press is running and the shaft D³ is rotated, then a rotary motion is transmitted by the gear wheels O, O', O³, O⁴, O⁵, O⁷ and the shafts O², O⁵ and I' to the combing wheels I, to rotate the latter in the direction of the arrow b'. It will also be noticed that when the combing wheels I rise and 80 fall the shaft O⁵ slides in the bearing C³, and when adjusting the bearings J on the side bars K of the swing frame according to the size of the sheets to be fed at the time, then the shaft O⁵ also slides in its bearing 85 C³ without disengaging the bevel gear wheel O⁴ from the bevel gear wheel O³, the collar O⁹ and spring O⁸ being adjusted correspondingly. It will be noted further that this rising and falling movement of the 90 combing wheels with respect to the sheet support is in substantially the same vertical plane—as a result of which the combing wheels can commence to act on the next underlying sheet as soon as the rear end of 95 the top sheet has passed the vertical center line of the combing wheel.

The side bars K of the swing frame are provided at their ends with adjustable weights K', to cause the combing wheels I 100 to bear down on the upper sheet B' with sufficient force to comb the uppermost sheets gradually rearward, as indicated in Figs. 2 and 4. The combing wheels I are lifted off the uppermost sheet B' when the latter is to be withdrawn from the pile by the action of the drawing rollers L' and the arms N, and in order to periodically raise and lower the combing wheels I the following arrangement is made: The bearings J are provided at the under side with rearwardly-extending bars J', attached at their rear ends to blocks J², slideable on the side bars K, and connected with each other by a cross bar J³. Collars J⁴ are mounted to slide on the side bars K, and are adapted to be secured thereto by set screws J⁵, and each collar J⁴ extends into an opening J⁶ formed on the corresponding bar J', so that when the set screws J⁵ are loosened, the connected parts, that is, the bearings J, bars J', J³ and the blocks J², J⁴, can be shifted lengthwise on the side bars K, to move the combing wheels I forward or rearward, according to the size of the sheets to be fed at the time. When the desired adjustment is made, the set screws J⁵ are screwed up to fasten the parts firmly in position on the side bars K of the swing frame, to swing with the latter up or down.

On the cross bars J^2 are fastened blocks P , to which are secured downwardly and forwardly extending spring arms P' and similar spring tongues P^2 , of which the spring tongues P^2 are arranged below the spring arms P' and are spaced from the same, so that the rear ends of the uppermost sheets can pass between the arms P' and the tongues P^2 on combing the uppermost sheets 10 rearward by the action of the combing wheels I .

The forward end of each spring arm P' is provided with an upwardly-extending lug P^3 , carrying a transverse pin P^4 , engaging 15 an elongated slot Q' in a toggle lever Q , pivotally connected with a toggle lever Q^2 , to swing loosely on the combing wheel shaft I' , so that the toggle levers Q , Q^2 can open and close, as indicated in Figs. 4 and 5, the 20 swinging movement of the said toggle levers being limited by a pin Q^3 , held on the toggle lever Q , and adapted to abut against stop lugs Q^4 , Q^5 , arranged on the toggle lever Q^2 . The toggle lever Q^2 is provided 25 with an upward extension Q^6 , on which is fulcrumed a spring-pressed pawl R , adapted to engage a ratchet wheel R' mounted to turn loosely on the shaft I' , and driven therefrom at a reduced speed, so that when 30 the pawl R is in engagement with the ratchet wheel R' , then the toggle levers Q , Q^2 are swung from their closed position shown in Fig. 4 into the open position shown in Fig. 5, whereby the free end of the 35 spring arm P' is pressed downward into contact with the uppermost sheets B' , and at the same time the combing wheels I are raised off the uppermost sheet, (see Fig. 5).

It is understood that when the toggle levers Q , Q^2 open, the free end of the spring arm P' is first pressed downward into contact with the uppermost sheet B' , thus preventing further downward movement of the free end of the spring arm P' , and as the 45 toggle levers Q , Q^2 continue to open or straighten out the shaft I' and with it the combing wheels I are raised off the uppermost sheet. When this takes place, the rearward combing of the uppermost sheets ceases 50 as the combing wheels I are now out of engagement with the uppermost sheet B' , but the sheets are held in position against movement for the time being by the free end of the spring arm P' bearing down on the uppermost sheet B' . The pawl R is normally held out of engagement by a lever R^2 , fulcrumed on the toggle lever Q^2 and pivotally connected by a link R^3 with one arm of a bell crank lever R^4 , fulcrumed on the corresponding block P , the other arm of the said bell crank lever R^4 being provided with a notch R^5 for engagement by the rear end of the uppermost sheet B' , so that when the said sheet is combed rearwardly by the 65 combing wheels I (see Fig. 4), and finally

engages the notch R^5 , then a swinging motion is given to the bell crank lever R^4 , which by the link R^3 swings the lever R^2 to the right, thus releasing the pawl R , to now swing downward into engagement with the ratchet wheel R' . The rotary motion of the latter now causes the toggle levers Q^2 , Q to swing into open position, as above described, and during this movement the pawl R is carried forward and finally engages a 75 fixed stop R^6 , which lifts the pawl R out of engagement with the ratchet wheel R' (see Fig. 5), thus allowing the lever R^2 , link R^3 and bell crank lever R^4 to return to normal position, to reengage the pawl R to allow 80 the toggle levers Q^2 , Q to swing back into closed position, as shown in Fig. 4. The bell crank lever R^4 is pressed on by a spring R^7 to hold the said bell crank lever R^4 , link R^3 and arm R^2 in the normal forward position to engage the pawl R .

On the cross bar J^2 are secured blocks S , adjacent to the blocks P previously mentioned, and on each block S are pivoted the links S' , S^2 , extending at angles one to the other and supporting a pawl S^3 , adapted to be engaged by one of a series of teeth T' formed on an arm T , adjustably secured to a rod T^2 by a set screw T^3 . The rear end of the rod T^2 is mounted to slide loosely in a bracket A' carried by the table A , and the forward end of the rod T^2 is pivotally connected with a crank arm T^4 , secured to a rock shaft T^5 , extending transversely and journaled in suitable bearings on the main frame C . One outer end of the shaft T^5 (see Fig. 6) is provided with a crank arm T^6 , pivotally connected by a link T^7 with a crank arm T^8 , attached to the driven shaft F previously mentioned, so that when the printing press is running an intermittent forward and backward sliding motion will be given to the rods T^2 . When the rods T^2 move forward in the direction of the arrow c' , then the toothed arms T engage the pawls S^3 and thus swing the same forward. When this takes place the links S' , S^2 cause the pawls S^3 to assume an inclined position and lift the blocks S , and with the same the cross bar J^2 and the side bars K of the swing frame, to raise the combing wheels I higher up and at the same time lift the spring arms P' out of engagement with the uppermost sheet B' (see Fig. 3).

In order to close the toggle levers Q^2 , Q , use is made of rods S^4 , pivotally connected with the forward ends of the pawls S^3 and slidably engaging tubes S^5 , fulcrumed on the pivotal connection between the toggle levers Q and Q^2 , and a spring S^6 is coiled on the rod S^4 and rests with one end on the tube S^5 and the other end is adapted to be engaged by a collar S^7 secured on the rod S^4 . A spring S^8 held on the block S presses the forward end of the pawl S^3 to hold the lat-

ter in the normal rearward position shown in Figs. 3 and 4. By the use of the spring S^6 and collar S^7 the toggle levers Q^2 , Q and connected parts are not liable to be broken 5 in case the pawl R should accidentally be in engagement with the ratchet wheel R' . When the carriage is lifted the bell crank lever R^4 is raised with it and hence the notch R^5 is drawn out of engagement with the top 10 sheet, thus permitting the arm R^2 to swing forward by its spring and engage the pawl R , for holding it out of contact with the ratchet wheel R' , while the toggle levers Q^2 , Q are returned to closed position. The parts 15 are held in this position until the combing device is again lowered and the arm R^4 is acted on by the next sheet.

In order to rotate the ratchet wheel R' at a reduced speed from the shaft I' , the following arrangement is made, special reference being had to Figs. 1 and 7: On the hub of the ratchet wheel R' is secured a gear wheel U , in mesh with a gear wheel U' , secured on a shaft U^2 , mounted to turn in 20 the bearing J and carrying a gear wheel U^3 in mesh with a gear wheel U^4 , secured on the shaft I' , so that when the latter is rotated a reduced rotary motion is transmitted by the gearing described to the ratchet 25 wheel R' .

The swing arm N , previously mentioned, is fulcrumed on an arm V , secured on a rock shaft V' , provided with an arm V^2 carrying a friction roller V^3 in peripheral engagement with a cam V^4 secured on the driven shaft F . A spring V^5 attached to the bracket H' presses the arm V so as to normally hold the friction roller V^3 in peripheral contact with the cam V^4 , and when the 30 printing press is running a rocking motion is given by the cam V^4 to the rock shaft V' , which, by the arm V , imparts a sliding motion to the arm N , the latter being inclined upwardly and rearwardly, as plainly indicated in Figs. 2 and 3. The under side of 35 the arm N is provided with a cam face N^2 , adapted to engage a cam face H' on the upper side of the fixed arm H^2 , so that when the arm N is moved rearwardly its cam face N^2 travels up the cam face H' , thus imparting a forward swinging motion to the arm N , to move the free end N' of the said 40 arm N toward the drawing roller L' , to press the forward end of the uppermost sheet B' against the said drawing roller L' . Two drawing rollers L' and a corresponding number of arms N are shown in the drawings, but it is evident that more of such devices or only one such device may be 45 used. When the arm N is in the normal position shown in Fig. 2, its free end N' rests on the free end of the arm H^2 and engages the forward end of the uppermost sheet B' then combed rearwardly by the 50 combing wheels I , until the forward end of

the uppermost sheet B' has just passed the free end N' of the arm N . Now when the arm N is moved rearwardly, its free end N' travels on the second uppermost sheet and passes under the forward end of the uppermost sheet B' , and on the further rearward sliding movement given to the arm N its cam surface N^2 travels up the cam face H' , so that the arm N is swung forwardly, thus lifting the forward end of the uppermost sheet B' and pressing it against the under side of the drawing roller L' . When this takes place the uppermost sheet B' is drawn forward off the pile of sheets B and passed between the feed rollers D , D' while being guided by the usual guides D^4 , D^5 extending rearwardly beyond the feed rollers D , D' . 70 75 80 85

The arm N is pressed on by a spring N^3 , attached to the arm V , so as to hold the arm N in engagement with the cam face H' of the fixed arm H^2 .

The operation is as follows: When the printing press is running and the several parts are in the position shown in Fig. 2, then the uppermost sheets of the pile of sheets B are combed rearwardly by the action of the combing wheels I , and when the uppermost sheet B' has just passed the free end N' of the arm N it engages the notch R^5 of the bell crank lever R^4 , to release the pawl R , so that the toggle levers Q^2 , Q are swung into open position, as previously explained, to engage the spring arm P' with the uppermost sheet B' and to lift the combing wheels I off the said uppermost sheet B' . 90 95 100 When this takes place the arm N is moved rearwardly and swung forwardly, as previously explained, to lift the forward end of the uppermost sheet B' and press the same in contact with the peripheral face of the drawing roller L' , and immediately previous to this result being accomplished the toothed arm T has acted on the pawl S^3 to impart an upward swinging motion to the swing frame, thus lifting the combing 105 wheels higher up and at the same time disengaging the spring arm P' from the uppermost sheet B' . The latter is now drawn forward off the pile of sheets by the action of the drawing roller L' , against which the sheet is held by the free end N' of the arm N . As soon as the feed rollers D , D' have taken hold of the forward end of the sheet B' then the arm N swings and slides back to normal position, and the swing frame carrying the combing wheels I and the spring arms P' is swung downward to normal position, so that the combing wheels I engage the now uppermost sheet B' of the pile, to comb the same rearward in the manner previously explained, it being understood that the combing wheels I drop immediately after the rear end of the uppermost sheet has passed the combing wheels I . 115 120 125 130

It is understood that the sheets in the pile

of sheets B are carried forwardly, and then the uppermost sheets, say four or five of them, are gradually combed rearwardly by the combing wheels I, and the front end of the 5 uppermost sheet B' is moved in engagement with the drawing roller L' to draw the uppermost sheet off the pile of sheets at the time the combing wheels I and the spring arms P' are in a raised position, that is, out 10 of contact with the uppermost sheet B'.

From the foregoing it will be seen that the sheets are fed singly and in rapid succession without danger of disarrangement of the sheets. It will also be noticed that 15 the devices shown and described permit of an exceedingly rapid feeding of the sheets, particularly as the combing wheels I come down from their raised position immediately after the rear end of the uppermost 20 sheet B' has been drawn forward a sufficient distance to clear the combing wheels I. Thus before the uppermost sheet B' is completely withdrawn from the pile of sheets B the combing wheels are active to comb the now 25 uppermost sheets rearward, and hence practically no time is lost, and by actual trial it has been possible to properly feed from eight to nine thousand sheets per hour.

Having thus described my invention, I 30 claim as new and desire to secure by Letters Patent:

1. A sheet feeding machine comprising a support for a pile of sheets, a combing device located adjacent to the rear end of the 35 sheet acted upon for combing the said sheet rearwardly, means for raising and lowering the combing device in substantially the same transverse vertical plane, timed to maintain the combing device in engagement with the 40 pile during the major portion of each cycle of the machine, and to raise it but momentarily to permit the tail end of the top sheet to pass forwardly of the plane of the combing device, and means for feeding the sheet 45 forwardly after it has been combed rearwardly located near the forward end of the pile and adapted to engage the top sheet after the combing device is raised to move the tail end of said sheet forwardly of the 50 plane of the combing device before the latter descends into contact with the pile, whereby the combing device and feeding means act simultaneously on different sheets in opposite directions.

2. A sheet feeding machine comprising a sheet support, a combing device, means for feeding the sheet forwardly after it has been combed rearwardly, means for intermittently raising and lowering the combing 60 device in substantially the same transverse vertical plane, timed to cause the combing device to engage the next underlying sheet immediately after the tail end of the top sheet has moved forward of the vertical 65 plane of the combing device, means actuated

by the rearward movement of the sheet for controlling the raising means, and means for imparting a rearward feeding motion to the combing device.

3. A sheet feeding machine comprising a 70 sheet support, means for moving the top sheet forwardly of the support, a combing device for moving the next underlying sheet rearwardly adapted to move up and down in substantially the same transverse vertical 75 plane, means for effecting the up and down movement of the combing device, timed so as to lower the combing device immediately after the tail end of the top sheet has passed the plane of the combing device, means actuated by the rearward movement of the sheet controlling the means for raising the combing device, whereby the two devices act 80 on separate sheets simultaneously in opposite directions. 85

4. A sheet feeding machine comprising a sheet support, a rotary combing device, means for feeding the sheet forwardly after it has been combed rearwardly, means for intermittently raising and lowering the 90 combing device in substantially the same transverse vertical plane, timed to cause the combing device to engage the next underlying sheet immediately after the top sheet has moved forward of the vertical plane of the 95 combing device, means actuated by the rearward movement of the sheet controlling the raising means, and means for imparting a rearward rotating feeding motion to the 100 combing device.

5. A sheet feeding machine comprising a sheet support, means for moving the top sheet forwardly off the support, a rotary combing device for moving the next underlying sheet rearwardly adapted to move up 105 and down in substantially the same transverse vertical plane, means for imparting a rearward rotating feeding movement to the combing device, means for effecting the up and down movement of the rotary combing 110 device, timed so as to lower the combing device immediately after the tail end of the top sheet has passed the plane of the combing device and timed so as to raise the combing device prior to the engagement of the 115 forward sheet moving means with the top sheet, and means actuated by the rearward movement of the sheet controlling the means for raising the combing device, whereby the two devices act on separate sheets simultaneously in opposite directions. 120

6. A feed mechanism provided with a fixed table supporting a pile of sheets, means for gradually carrying the sheets forward over the said table, rotary combing wheels 125 above the table and the pile of sheets, for gradually and intermittently combing the uppermost sheets rearward, means for intermittently raising and lowering the said combing wheels, a transferring device for 130

ward of the said table for engagement with the forward end of the uppermost sheet for drawing the latter off the pile of sheets at the time the combing wheels are out of contact with the uppermost sheet.

7. A feed mechanism provided with a fixed table supporting a pile of sheets, means for gradually carrying the sheets forward over the said table, rotary combing wheels located above the pile of sheets and adapted to contact with the uppermost sheets to comb the same rearward, a pressing device for the uppermost sheet, means for initially raising the combing wheels off the uppermost sheet and pressing the latter down on the pile by the said pressing device, final raising means for the said combing wheels and the said pressing device, and a transferring device forward of the table for engagement with the forward end of the uppermost sheet at the time the said pressing device is down on the sheet, and means for drawing the uppermost sheet off the pile of sheets at the time the said pressing device is raised out of engagement with the uppermost sheet.

8. A feed mechanism comprising forward conveying means for gradually carrying the sheets of a pile of sheets forward, rotary combing wheels for gradually combing the uppermost sheets rearward, a pressing device for pressing the uppermost sheet, means connected with the said pressing device and the said combing wheels to initially raise the combing wheels off the uppermost sheet and force the said pressing device in engagement with the uppermost sheet, means for lifting the pressing device off the uppermost sheet, and a delivery device for engaging the forward end of the uppermost sheet at the time the said sheet is engaged by the pressing device and for removing the uppermost sheet immediately after the sheet is disengaged by the said pressing device.

9. A feed mechanism, comprising a combing wheel, adapted to comb the uppermost sheets gradually rearward, means for intermittently moving the said combing wheel in and out of contact with the uppermost sheet of the pile of sheets, a pressing device for pressing the uppermost sheet on the pile and subsequently releasing it, a revolute drawing roller in front of the combing wheel, and transferring means for engaging the forward end of the said uppermost sheet at the time the said pressing device engages the uppermost sheet, the said transferring means pressing the sheet in contact with the said drawing roller at the time the sheet is released by the pressing device whereby the drawing roller draws the uppermost sheet off the pile.

10. A feed mechanism, comprising a combing wheel adapted to comb the uppermost sheets gradually rearward, means for intermittently moving the said combing

wheel in and out of contact with the uppermost sheet of the pile of sheets, a pressing device for pressing the uppermost sheet on the pile and subsequently releasing it, a revolute drawing roller in front of the 70 combing wheel, and a movable arm adapted to engage the forward end of the said uppermost sheet at the time the said pressing device engages the uppermost sheet, the said movable arm pressing the sheet in contact 75 with the said drawing roller at the time the sheet is released by the said pressing device, whereby the drawing roller draws the uppermost sheet off the pile of sheets.

11. A feed mechanism provided with a 80 combing means for gradually combing the uppermost sheets of a pile of sheets rearward, a drawing roller, and an arm adapted to pass under the forward end of the uppermost sheet and raise the said forward end 85 into drawing contact with the said drawing roller.

12. A feed mechanism provided with a combing means for gradually combing the uppermost sheets of a pile of sheets rearward, a drawing roller above the forward portion of the pile of sheets, and an arm having a sliding and swinging motion adapted to rest normally on the forward end of the uppermost sheet until the latter is 95 combed rearwardly and out from under the said arm, the latter then passing under the forward end of the uppermost sheet and raising the said forward end into drawing contact with the said drawing roller. 100

13. A feed mechanism provided with a table, means for moving a pile of sheets forward over the table, a curved spring plate at the forward end of the table, and onto which the forward end of the said pile 105 of sheets is fed by the sheet moving means, a drawing roller, and means for engaging the forward end of the uppermost sheet above the said spring plate and for raising the said sheet end into drawing contact with 110 the said drawing roller.

14. A feed mechanism provided with a table, means for moving a pile of sheets forward over the table, a curved spring plate at the forward end of the table and onto 115 which pass the forward end of the said pile of sheets, a drawing roller, an arm mounted to swing and to slide and adapted to pass under the forward end of the uppermost sheet and into drawing contact with the said drawing roller, and means for imparting a swinging and sliding motion to the said arm.

15. A feed mechanism, comprising a revolute combing wheel adapted to comb the uppermost sheets of a pile of sheets gradually rearward, raising and lowering means for intermittently moving the said combing wheel in and out of contact with the uppermost sheet of the pile, a revolute drawing 120

roller in front of the said combing wheel, an arm adapted to pass with its free end under the forward end of the said uppermost sheet, and means for imparting a sliding and swinging motion to the said arm for the latter to move the forward end of the uppermost sheet into contact with the said drawing roller for drawing the uppermost sheet off the pile at the time the said 10 combing wheel is out of contact with the said uppermost sheet.

16. A feed mechanism, comprising a revolute combing wheel adapted to comb the uppermost sheets of a pile of sheets gradually rearward, raising and lowering means for intermittently moving the said combing wheel in and out of contact with the uppermost sheet of the pile, a revolute drawing roller in front of the said combing wheel, an arm adapted to pass with its free end under the forward end of the said uppermost sheet, means for imparting a sliding and swinging motion to the said arm for the latter to move the forward end of the uppermost sheet into contact with the said drawing roller for drawing the uppermost sheet off the pile at the time the said combing wheel is out of contact with the said uppermost sheet, means for stopping 25 the rearward motion of the said uppermost sheet, and means for controlling the initial movement of the said raising and lowering means.

17. A feed mechanism, comprising a table for supporting a pile of sheets, intermittent conveying means for intermittently conveying the sheets forward over the said table, a combing wheel above the uppermost sheet of the pile of sheets, a shaft carrying the 30 said combing wheel, a rocking support for the said combing wheel shaft to raise and lower the said combing wheel and move it in and out of contact with the said uppermost sheet, means for rotating the said 35 combing wheel shaft, means for imparting a swinging movement to the said support, a revolute drawing roller arranged in front of the said combing wheel, and an arm mounted to swing and to slide and adapted to engage the forward end of the said uppermost sheet and move it in contact with the said drawing roller at the time the said 40 combing wheel is in raised position.

18. A feed mechanism, comprising a table for supporting a pile of sheets, intermittent conveying means for intermittently conveying the sheets forwardly over the said table, a combing wheel above the uppermost sheet of the pile of sheets for combing the uppermost sheets of the pile of sheets rearward, a shaft carrying the said combing wheel, a rocking support for the said combing wheel shaft to raise and lower the said combing wheel and move it in and out of contact 45 with the said uppermost sheet, means for

rotating the said combing wheel shaft, initial raising means for imparting an initial raising motion to the said combing wheel, a stop for limiting the rearward motion of the said uppermost sheet and controlling the 50 said initial raising means, means for imparting an upward swinging motion to the said support, a revolute drawing roller arranged in front of the said combing wheel, and an arm mounted to swing and to slide 55 and adapted to engage the forward end of the said uppermost sheet and move it in contact with the said drawing roller at the time the said combing wheel support is in raised position.

19. A feed mechanism, provided with a rearward combing device, comprising a combing wheel for engagement with the uppermost sheet of a pile of sheets and mounted to turn to feed the uppermost sheet rearward, a shaft carrying the said combing wheel, a swinging support carrying the said shaft and provided with a spring arm adapted to rest on the said uppermost sheet, a stop lever mounted on the said support for 60 limiting the rearward motion of the said uppermost sheet, and a mechanism intermediate the said shaft and the said spring arm and controlled by the said stop lever for initially raising the combing wheel off the 65 said uppermost sheet.

20. A feed mechanism, provided with a rearward combing device comprising a combing wheel for engagement with the uppermost sheet of a pile of sheets and mounted to turn to feed the uppermost sheet rearward, a shaft carrying the said combing wheel, a swinging support carrying the said shaft and provided with a spring arm adapted to rest on the said uppermost sheet, a stop lever mounted on the said support for 70 limiting the rearward motion of the said uppermost sheet, toggle levers interposed between the said shaft and the said spring arm, a ratchet wheel on the said shaft, a pawl for engagement with the said ratchet wheel and mounted on the toggle lever connected with the said shaft, a pawl-supporting arm fulcrumed on the said toggle lever and adapted to hold the said pawl normally 75 out of engagement with the said ratchet wheel, and a link connecting the said pawls supporting arm with the said stop lever.

21. A feed mechanism, provided with a rearward combing device comprising a combing wheel for engagement with the uppermost sheet of a pile of sheets and mounted to turn to feed the uppermost sheets rearward, a shaft carrying the said combing wheel, a swinging support carrying the said shaft and provided with a spring arm adapted to rest on the said uppermost sheet, a stop lever mounted on the said support for limiting the rearward motion of the said uppermost sheet, toggle levers interposed be- 80 85 90 95 100 105 110 115 120 125 130

- between the said shaft and the said spring arm, a ratchet wheel on the said shaft, a pawl for engagement with the said ratchet wheel and mounted on the toggle lever connected with the said shaft, a pawl-supporting arm fulcrumed on the said toggle lever and adapted to hold the said pawl normally out of engagement with the said ratchet wheel, a link connecting the said pawl-supporting arm with the said stop lever, and a fixed arm for engagement by the said pawl for throwing the latter out of engagement with the said ratchet wheel.
22. A feed mechanism, provided with a rearward combing device, comprising a combing wheel for engagement with the uppermost sheet of a pile of sheets and mounted to turn to feed the uppermost sheets rearward, a shaft carrying the said combing wheel, a swinging support carrying the said shaft, a pawl hung on the said support, and a reciprocating notched bar for engaging the said pawl to impart a swinging motion to the said support.
23. A feed mechanism, provided with a rearward combing device comprising a combing wheel for engagement with the uppermost sheet of a pile of sheets and mounted to turn to feed the uppermost sheets rearward, a shaft carrying the said combing wheel, a swinging support carrying the said shaft, a pair of arms pivoted on the said support and standing at an angle one to the other, a pawl pivoted on the said pair of arms, and a reciprocating notched bar adapted to engage the said pawl to impart a swinging motion to the said support.
24. A feed mechanism, provided with a rearward combing device comprising a combing wheel for engagement with the uppermost sheet of a pile of sheets and mounted to turn to feed the uppermost sheets rearward, a shaft carrying the said combing wheel, a swinging support carrying the said shaft, a pair of arms pivoted on the said support and standing at an angle one to the other, a pawl pivoted on the said pair of arms, a reciprocating notched bar adapted to engage the said pawl to impart a swinging motion to the said support, and a resistance spring for the said pawl.
25. A feed mechanism, provided with a revolute drawing roller, a transferring arm for engaging the forward end of the sheet of paper to be fed and pressing it against the peripheral face of the said drawing roller, an intermittently swinging arm on which the said transferring arm is fulcrumed, a fixed arm, and cam faces on the said fixed arm and the said transferring arm and adapted to engage one the other for imparting a swinging motion to the said transferring arm.
26. A feed mechanism, provided with a table for supporting a pile of sheets, an endless belt having its upper run passing over the said table to gradually move the sheets forward, a roller over which passes the said belt, a pawl and ratchet mechanism for imparting an intermittently rotary motion to the said roller, an arm carrying the said pawl, a cross head connected with the said arm and having a tooth, a shaft on which the said cross head is mounted to slide, a cam on the said shaft for imparting a reciprocating motion to the said cross head, and a pawl controlled by the uppermost sheets and adapted to engage the said tooth.
27. A feed mechanism, provided with a support having an arm and a tongue spaced from the arm for the reception of the rear end of the uppermost sheets of a pile of sheets to be fed forward, a combing wheel mounted to rotate on the said support for combing the uppermost sheets between the said arm and tongue, and means for imparting an up and down swinging motion to the said support.
28. In combination with a feed table, means for feeding a pile of sheets forwardly over the feed table, a drawing roller over the forward end of the feed table, an elevating arm for lifting the topmost sheet against the drawing roller, means for combing the topmost sheet rearwardly from under the elevating arm while the arm is in lowered position, and means for actuating the arm to push it in under the sheet so withdrawn and then to lift the sheet against the drawing roller.
29. In combination with a feed table, means for feeding the sheets forwardly over the feed table, a drawing off device over the forward end of the table, an elevating arm for lifting the topmost sheet into engagement with the drawing off device and adapted in its lowered position to overlie the forward edge of the sheets, means for combing the sheets rearwardly from under the elevating arm, and means for actuating the elevating arm to slide it in under the top sheet thus withdrawn and lift the top sheet into engagement with the drawing off device.
30. The combination with a feed table, means for feeding a pile of sheets forwardly over the table, an elevating device adapted in lowered position to overlie the forward edge of the top sheet, combing devices for combing the sheets rearwardly to withdraw the edge of the top sheet from under the elevating device, and means actuating the elevating device to move it in under the forward edge of the topmost sheet and then to lift said sheet above the top of the pile.
31. In a sheet feed mechanism, the combination with feeding off devices, combing

devices for combing the topmost sheets of a pile rearwardly away from the feeding off devices, means for tripping the combing devices when the top sheet has reached a rearward most position, and means for elevating the sheet into engagement with the feeding off devices.

32. The combination with a feed table adapted to support a pile of sheets, a feeding off device at the forward end of the sheet support, combing devices acting on the top of the pile to comb the sheets rearwardly with respect to the feeding off device, means for tripping the action of the combing devices when the sheets have been combed rearwardly a certain distance, and means for feeding the pile forwardly into position for engagement by the combing devices and means for engaging the uppermost sheet, after being combed rearwardly, with the feeding off device.

33. In a sheet feeding mechanism, a combing wheel for engagement with the uppermost sheet of a pile of sheets, a shaft on which the combing wheel is mounted, a movable support carrying said combing wheel shaft, a pawl hung on the said support, and a reciprocating member for engaging with said pawl for the purpose of raising the movable support and the combing wheel carried thereby.

34. The combination with a sheet support for supporting a pile of sheets, of a combing device mounted above the sheet support, means for feeding the pile of sheets forwardly under the combing device, and means operating the combing device to cause said device to comb the uppermost sheets of the pile rearwardly, whereby to effect the separation of the uppermost sheets in the pile.

35. In combination with a sheet support, a feeding off device at the forward end of the sheet support, a combing device mounted above the sheet support, means for feeding a pile of sheets forwardly over the sheet support to a position beneath the combing device, means operating the combing device to cause said device to comb the uppermost sheets rearwardly to effect the separation of the uppermost sheets, and means for engaging the separated top sheet with the feeding off device.

36. In a sheet feeding mechanism, a combing wheel for engagement with the uppermost sheet of a pile of sheets, a shaft on which the combing wheel is mounted, a movable support carrying the combing wheel shaft, a pawl hung on the said support, a rack arranged when in engagement with the pawl to sustain the movable support and the combing wheel carried thereby, and means for effecting the engagement of the rack and pawl.

37. The combination with a feed table, of a combing wheel mounted above the feed table, a guideway supported above the feed table and disposed in rear of the combing wheel, means for feeding a pile of sheets forwardly over the feed table beneath the guideway and combing wheel into a position to be acted upon by the combing wheel, and means for operating the combing wheel to comb the uppermost sheets rearwardly into the guideway aforesaid.

38. The combination with a feed table, of a combing wheel mounted above the feed table, a guideway supported above the feed table and disposed in rear of the combing wheel, means for feeding a pile of sheets forwardly over the feed table beneath the guideway and combing wheel into a position to be acted upon by the combing wheel, means for operating the combing wheel to comb the uppermost sheets rearwardly into the guideway aforesaid, means for tripping the combing wheel, and a trip finger controlling the said tripping means, disposed in the guideway so as to be engaged by the uppermost sheet combed by the combing wheel.

39. In combination with a sheet support, means for feeding a pile of sheets forwardly over the said support, a guideway at the forward end of the sheet support arranged to receive the forward edges of the uppermost sheets advanced by the feeding means, a combing device mounted above the sheet support arranged to comb the uppermost sheets rearwardly to free their forward edges of the guideway at the forward end of the sheet support, a feeding off device, and means for engaging the forward edge of the uppermost sheet, after it has been withdrawn from the guideway, with the feeding off device.

40. The combination with a sheet support, means for feeding a pile of sheets forwardly over said sheet support, and a combing device mounted above the sheet support and arranged to comb the uppermost of the pile of sheets rearwardly, of means for tripping the feeding means when the pile of sheets has been advanced over the sheet support to a predetermined point, and means for tripping the combing device when the uppermost sheet of the pile has been combed thereby to a predetermined rearward position.

41. In a sheet feeding machine, the combination of a sheet support, means for feeding a bank of sheets forwardly over the sheet support, means for combing the uppermost sheets rearwardly, and means for feeding the rearwardly combed, topmost sheet forwardly off the bank.

42. In a sheet feeding machine, the combination of a sheet support, sheet guides at the forward end of the sheet support, means for feeding a bank of sheets forwardly over

the sheet support to position under the guides, means for combing the topmost sheet rearwardly from under the guides, and means for feeding the rearwardly combed topmost sheet forwardly over the guides.

5 In testimony whereof I have signed my

name to this specification in the presence of two subscribing witnesses.

LYMAN MIDDLEDITCH.
